JOHN W. MARR, OF NEWPORT BEACH, CALIFORNIA.

AUTO-THEFT SIGNAL.

1,350,032.

Specification of Letters Patent. Patented Aug. 17, 1920.

Application filed February 25, 1920. Serial No. 361,336.

To all whom it may concern:

Be it known that I, JOHN W. MARR, a citizen of the United States, residing at Newport Beach, in the county of Orange 5 and State of California, have invented new and useful Improvements in Auto-Theft Signals, of which the following is a specification.

This invention relates to motor vehicles 10 and has for its object to provide a simple and effective theft signal therefor, and the invention consists of the construction, the combination and in details and arrangements of the parts, an embodiment of which 15 invention is illustrated in the accompanying drawings and described and claimed herein.

Figure 1 is a perspective of the portion of the tonneau of an automobile to which the theft signal is applied in combination 20 with the exhaust pipe from the motor, the latter not being shown.

Fig. 2 is a transverse sectional view in a plane at right angles to the axis of the valve device of the signal.

Fig. 3 is a section on line 3—3 of Fig. 2 in a plane at right angles to the plane of Fig. 2.

The present invention contemplates the provision of a signal giving device that may be connected to the exhaust apparatus of an 30 internal combustion engine of a motor driven vehicle so that the pressure of the exhaust gases can be utilized to give an audible signal.

In the accomplishment of this a valve casting or shell 2 in the form of a circular and flat disk is provided with a cylindrical chamber open at one end, and in this chamber there is fitted a rotary or oscillating valve disk or part 3 of hollow structure that 40 is cut away on one side at the chordal line 4 so as to remove a portion of the peripheral wall 3^a of the valve member. This valve member is circumferentially turned to have a snug working fit in the chamber of the shell 2 about the axis of the shell through 45 one side of which extends an axial stem 5 of the adjacent end wall of the valve 3. The opposite end wall of this valve has a flange 3^b overlapping the adjacent surface of the 50 valve shell 2 and on the stem 5 is provided a set of clamp nuts 6 adjustable to draw the valve 3 into suitable running fit in its shell 2.

On one side of the shell there is provided an inlet connecting pipe 7 forming a branch 55 of the exhaust stem of the motor, not shown, of the vehicle, and at a diametrically oppo-

site point in the shell is an outlet connection 8 that may be attached to the usual exhaust muffler, not shown. Intermediately between these connections 7 and 8 there is provided 60 an outlet 9 that might be termed the cut-out. At a position approximately diametrically opposite the cut-out 9 the end wall of the shell 2 is provided with a port 10 to which may be attached means for giving the 65 audible signal desired, such means comprising, for instance, a whistle 11.

When the valve 3 is thrown by a lever 13 on its stem 5 to the position shown in Fig. 2 the annular wall 3^a of the valve member 3 70 uncovers the inlet connection 7 and also uncovers the whistle port 10 so that the pressure of the exhaust gases can be utilized to vibrate the whistle. If the lever be thrown from the position shown in Fig. 2 so as to 75 engage an intermediate seat or notch 14 in a wearing plate 15 shown as mounted in the foot board F of the vehicle V, then the gases passing into the valve parts from the connection 7 will pass out of the cut-out 9 80 by the registration therewith of the coördinate cut-out port 9^a provided therefor in the annular wall 3^a.

If it be desired to divert the exhaust gases 85 through the valve to the muffler connection 8 then the valve lever 13 is thrown over so as to engage a seat or notch 16 on the wear plate 15 at which time a muffler connection port 8^a in the annular wall 3^a of the valve 90 will be brought into register with the muffler connection 8.

In the operation of the device the authorized driver of the vehicle will throw the lever 13 of the valve, during the ordinary operation of the vehicle, so as to open communication between the connections 7 and 8 95 by registering the outlet port 8^a with the connection 8 and the discharge will pass into the muffler. Or, the operator can throw the lever 13 to set the valve so as to register with 100 port 9^a with the cut-out 9 in ordinary operating conditions.

When the driver desires to park the car or let it remain at a given station he then throws the lever 13 over to the position 105 shown in Figs. 2 and 3 at which time it is locked as to the wear plate 15 by a padlock P the shackle of which is passed through an aperture 13^a provided in the lever and through a complementary fixed lug 17, so 110 that when the engine is started with the valve in the open position, as shown, the ex-

haust gases will serve to give a signal through the whistle device 11 and this whistling sound will be continued until the engine is stopped or the lever 13 shifted to 5 cut off the whistle signal.

Various changes may be made without departing from the spirit of the invention as claimed.

What is claimed is:

- 10 1. In a theft signal for motor vehicles, the combination of a circular valve casing adapted to be attached to the exhaust outlet, a whistle attached to said casing adapted to be sounded by exhaust gases, outlets to atmosphere and to a muffler from said casing, the said outlets and exhaust pipe connection being disposed radially about the periphery of said casing, a valve revolubly mounted within said casing comprising an arcuate 15 wall adapted to slidably contact with the inner circular surface of said casing, ports in said valve adapted to register with outlets in said casing, and means to rotate said valve.
- 20 2. A theft signal for motor vehicles, the
- 25

combination of a circular valve casing adapted to be attached to the exhaust outlet, a whistle attached to the end wall of such casing and adapted to be sounded by exhaust gases, outlets to atmosphere and to a muffler from said casing, a valve revolubly mounted within the said casing comprising a wall having a peripheral flange, said flange adapted to slidably contact with the inner peripheral surface of the casing, ports in said flange adapted to alternately register with the outlets to atmosphere and the muffler, the said valve wall and flange being truncated on a chordal line so that when the valve ports are brought into registration 30 with either of the outlets in the casing the valve wall will cover the whistle port, and when the whistle port is uncovered by the said wall the said outlets will be covered, and means to lock said valves in any of the 35 covering or uncovering portions.

In testimony whereof I have signed my name to this specification.

J. W. MARR.
